UNITED STATES PATENT OFFICE

101,433

DESIGN FOR A COMBINED RADIATOR SHELL AND HEAD LAMP

Edwin Zohrer, North Tarrytown, N. Y.

Application July 3, 1936, Serial No. 63,630

Term of patent 14 years

To all whom it may concern:

Be it known that I, Edwin Zohrer, a citizen of the United States, residing at Sleepy Hollow Manor, North Tarrytown, in the county of Westchester and State of New York, have invented a new, original, and ornamental Design for a Combined Radiator Shell and Head Lamp, of which the following is a specification, reference being had to the accompanying drawing, forming part thereof.

Figure 1 is a front elevation;

Figure 2 is a side elevation;

Figure 3 is a plan view; and

Figure 4 is a front perspective view of a combined radiator shell and head lamps showing my new design.

The dominant feature of the design resides in the shape of the head lamps and radiator shell and in the manner in which the head lamps are merged into the shell portion.

What I claim is:

The ornamental design for a combined radiator shell and head lamp substantially as shown and described.

EDWIN ZOHRER.
